UNITED STATES PATENT OFFICE

GEORGE K. CULP, OF DOWAGIAC, MICHIGAN, ASSIGNOR TO TIME-O-STAT CONTROLS COMPANY, OF ELKHART, INDIANA, A CORPORATION OF MARYLAND

DESIGN FOR A HOUSING FOR A PORTABLE THERMOSWITCH

Application filed December 23, 1929. Serial No. 33,906. Term of patent 7 years.

To all whom it may concern:

Be it known that I, GEORGE K. CULP, a citizen of the United States, residing at Dowagiac, in the county of Cass and State of Michigan, have invented a certain new, original, and ornamental Design for Housing for a Portable Thermoswitch, of which the following is a specification, reference being had to the accompanying drawing, forming a part thereof.

The figure shows a front perspective view

of a portable thermoswitch incorporating the ornamental housing of my new design.

The rear face of the device presents substantially the same appearance as the front face, with the exception that it does not carry a thermometer.

I claim:

The ornamental design for a housing for a portable thermoswitch substantially as shown and described.

GEORGE K. CULP.
